FORM FEEDING MECHANISM FOR
TYPEWRITERS

Arthur H. Sharpe, West Hartford, Conn., assignor
to Underwood Corporation, New York, N. Y., a
corporation of Delaware

Application June 19, 1948, Serial No. 34,034

11 Claims. (Cl. 197—133)

1

This invention relates to typewriting and other record making machines, and more particularly to mechanism for quickly feeding work forms especially of a continuous strip, into and out of typing position. The typing may proceed, for a succession of forms, on the continuous strip conveyed past the typewriter printing line by means of a feed roll or platen, driven preferably by power for variable extents of paper feed.

An object of this invention is to provide an efficient, preferably power-driven mechanism operable, after a form has been typed, to impart to a roll or typewriter platen a required rotation or sweep of comparatively large extent so as to speedily bring the first typing line of a succeeding form to the printing line.

Another object is to provide such a mechanism for a carriage-carried, revolvable roll or platen of a typing machine and efficiently in a manner so that the carriage mounting the platen may move in letter-space and return directions unimpaired by the presence of such mechanism.

It is also an object of this invention to utilize efficiently a motor mounted in the base of the typewriter as the source of power for so rotating the carriage-carried paper-feed mechanism.

Another object is to provide an efficient automatically operative overthrow prevention mechanism for the paper-feeding means, said mechanism being transitorily operative at the end of each sweep feed of the roll or platen to prevent further rotation thereof, and being automatically restored to a normal ineffective position so as not to interfere with ordinary rotation of the platen by the usual end-knobs or the line-spacing mechanism.

A still further object is to provide efficient, reliably operative means to have such form-feed mechanism operable only when the paper carriage is in a predetermined, fully returned position.

It is also an object to provide a manually operable key located in a convenient position on the typewriter for effecting the form-feeding operation.

Another objective of the invention is to provide a mechanism of the above noted character which is simple in design, efficient, and which requires a minimum amount of change in the construction of the typewriter.

Other objects, features, and advantages will be apparent from the following description of a preferred embodiment of the invention.

In the drawings:

2

Figure 1 is a right side view, partly in section, of a portion of a typewriter showing the invention applied thereto.

Figure 2 is a top view showing the typewriter platen and a portion of the base frame with the carriage and frame-carried sections of the form-feeding mechanism.

Figure 3 is a rear view of the right-hand end of the typewriter showing the driving parts and an interlock between the conventional carriage return mechanism and the paper-feeding device.

Figure 4 shows the paper-feed drive clutch of Figure 1 at the time of its release.

Figure 5 is a view similar to Figure 4 but showing the clutch at a later point in its cycle.

Figure 6 is a front view, partly in section, of the form-feed drive clutch and its connection to the carriage-carried drive mechanism.

Figure 7 is a side view taken along the line 1—1 of Figure 2 and showing the overthrow preventing means in the normal position.

Figure 8 is a view similar to Figure 7 but showing the parts in the effective position.

Figure 9 is an enlarged top view of a detent releasing means shown in Figure 7, and

Figure 10 is an example of the forms used in the machine of the present invention.

The invention is disclosed as embodied in the well-known Underwood Electric Typewriter and therefore only so much of the typewriter as is required to illustrate the application thereto of the mechanism of the invention will be described herein.

General description

The machine as described herein is designed for typing the toll bills of the telephone companies. These toll bills are supplied in the form of long strips with the appropriate headings printed at properly spaced intervals thereon. The strip is placed in the machine by passing it from the rear under the platen and up in front thereof. To the end of obtaining the proper operating condition of the form-feed mechanism, the platen is first manually rotated in a reverse direction until it is arrested. Then the paper strip is adjusted to position the first printing line on the leading form at the printing point, and the machine is ready for use.

The data identifying the party whose bill is being made out and the date are first typed. The carriage is then returned to the right by depression of the usual carriage return key and the first toll charge is typed out. The carriage 55 is returned and the platen is line spaced auto-

matically at the end of each typing line by the usual carriage return drive means.

After the last item has been typed and the carriage has automatically returned to the beginning of the next line, a form feed is initiated by depression of a special key in the keyboard. This key when depressed will engage a one-revolution clutch to connect a frame-carried splined shaft and a continuously driven member. The form-feed drive for the platen is driven from the splined shaft by way of a gear which partakes in the movements of the carriage and which is slidable on the shaft and includes a gear concentric with the platen shaft and carrying a spring-pressed pick-up pawl for the platen. A lug on the platen is initially positioned in contact with this pawl by rotating the platen manually reversely. As the platen is line-spaced in the course of typing each form, this lug moves away from the pawl. The initial rotation imparted to this gear and pawl by the form-feed drive is thus idle until the pawl engages the lug, the form-feed mechanism being constructed to turn the platen just sufficiently to advance the first typing line of the next form to printing position.

A novel overthrow prevention device is provided to engage a ratchet wheel on the platen at the end of each sweep feed, thereby to stop the platen from further rotation. The overthrow device is engaged with such ratchet under control of the drive mechanism but is released from its engaging position only when it has checked the rotation of the platen.

Although the platen sweep-feed mechanism is capable of advancing the forms at any carriage position, it is desirable that the forms be advanced only when the carriage is in its fully returned position and for this reason, a form-feed clutch operating linkage is provided with a carriage-controlled connection which renders an operation of the form-feed key ineffective at any other carriage position. The form-feed mechanism and the carriage return mechanism may not operate simultaneously since both will cause a feed of the platen. An interlock to prevent such simultaneous operation of these two mechanisms has therefore been provided. The combination of these two safety mechanisms will permit the platen drive to be actuated only when the carriage is in the fully returned position and will permit the carriage return mechanism to be engaged with its drive at any advanced point in the carriage movement only providing the form-feeding operation resultant from the prior depression of the form-feed initiating key has been concluded.

Detailed description

The typewriter to which the present invention is applied is, as has been mentioned, the well-known Underwood Electric and for that reason only so much of the structure as cooperates with the new structure has been shown herein. The base 11, Figure 1, carries a constantly running motor 12 and a pair of side plates 13, only the right-hand plate being shown herein. Mounted between the side plates 13 is a carriage guide rail 14 on which rides a paper carriage 15. The carriage 15 is fed in letter-spacing direction by a spring-driven drum 16 mounted between the side plates 13 and connected to the carriage 15 by the usual flexible tape, not shown. A rack 17 on the carriage 15 normally engages an escapement-controlled pinion gear 18 to control the letter space feed of the carriage 15. The carriage 15 may be returned

to its initial starting position by a manually or carriage controlled return mechanism similar to that shown in the Helmond Patent No. 2,262,676, issued November 11, 1941. The gear 19, clutch 20, bell crank 21, link 22, clutch-operating lever 23 and shaft 24, Figure 3, correspond to elements 112, 124, 127, 152, 153 and 113 of said Helmond patent, and constitute the clutch and clutch-engaging mechanism for the carriage return drive. Gear 19 is fixed to shaft 24 and engages a gear, not shown, driven by the motor 12 so that shaft 24 is continuously driven during operation of the typewriter. A platen feed drive pulley 25 is fixed to the outer end of shaft 24.

Platen feed mechanism

A splined shaft 28 is journaled in the upper rear corner of the right side plate 13 and in a bracket 29 fixed to the tabulator reed frame 30, see element 72 of the Helmond Patent No. 2,262,676, noted above. Shaft 28 carries, outside of plate 13, a pulley 31 which is freely rotatable on a reduced end of shaft 28 and is retained thereon by a split washer 32, Figure 6, snapped into a groove in the end of shaft 28. A belt 33, kept taut by an idler roller 34, continuously transmits a drive from pulley 25 to pulley 31. The inner hub 35 of pulley 31 is toothed to form the drive element of a clutch for shaft 28. Fixed to shaft 28 between the side plate 13 and pulley 31 is a disc 36 provided with a notch 37 and a clutch pawl 38, the pawl 38 being pivoted on the outer side of disc 36 on a stud 39. Pawl 38 is formed with a lug 40 thereon to engage the toothed hub 35 of pulley 31 and is tensioned for movement into clutch-engaging position by a spring 41 connected between the free end of pawl 38 and a stud 42 on disc 36. Pawl 38 is normally retained in its ineffective position by a bell crank 43 which engages under a square stud 44 fixed to the free end of pawl 36 and projecting through notch 37 in the disc 36. Bell crank 43 is pivoted on a stud 45 fixed in the side plate 13 and is manually operable under control of a key 46 in the typewriter keyboard to swing clear of the stud 44, and thereby to institute a single cycle of shaft 28. Key 46 is fixed to a key lever 47 which is pivoted on the usual key lever pivot rod 48 and is provided with a restoring spring 49. The rearward extension of key lever 47 underlies a shoulder 50 of a vertical slide 51, Figure 3, mounted slidably at its lower end by a stud 52, and further mounted slidably near its upper end in an endwise enlarged slot in a bracket 53, both stud 52 and bracket 53 being secured to a plate 54 fixed to a bar 55 between the right and left-hand side plates 13. The upper end of slide 51 is notched to provide a shoulder 56 which is normally positioned under a square stud 57 on an arm 60 pivoted to bracket 54 and extending through a slot 61 in the right side plate 13.

Pivoted at 62, Figures 1, 4 and 5, on plate 13 and resting on arm 60 is an arm 63 carrying a pawl 64 pivoted thereon at 65 and provided with an upward extension 69. A spring 66 connected between a stud 67 on plate 13 and a stud 68 on pawl 64 normally maintains arm 63 in overlying relation against arm 60, and further maintains the stud 68 on pawl 64 forwardly swung to a limit established by contact of the stud 68 against the upper edge of arm 63 as shown in Figure 1. In the normal position of pawl 64, a square stud 70 thereon underlies idly a rearward arm of bell crank 43, previously described. When the arm 75 63 is lifted as a result of the depression of the

key 46, the bell crank 43 is displaced counter-clockwise by the pin 70 and will release clutch pawl 38. A latch lever 71, also pivoted on plate 13 on a stud 72, has a tooth 73 on its lower arm and further has a bent-off ear 74 on the upper arm. A spring 75 between latch lever 71 and bell crank 43 serves to normally maintain these parts in their Figure 1 position in which the tooth 73 bears against the rear side of arm 60 and in which the bell crank 43 is retained in clockwise moved position with its forward arm in contact with a stud 76 on end plate 13. Disc 36 is also provided with a pin 77 on its inner side for co-operation with the extended arm 69 of pawl 64.

Operation of platen feed clutch

The mechanism thus far described is operative to give a single cycle of rotation to shaft 28 for each operation of key 46. Depression of key 46 will rock bell crank 43 counterclockwise by way of slide 51, Figure 3, arm 60, arm 63, Figure 1, and stud 70 of pawl 63. Such rotation of bell crank 43 releases clutch pawl 38 which is therewith pulled by spring 41 to engage the tooth 40 with the constantly rotating toothed hub 35 of pulley 31. Movement of pawl 38 to its engaging position moves square stud 44 from engagement with the back of ear 74 of latch lever 70 whereupon spring 75 rotates lever 70 clockwise to position latch tooth 73 under arm 60 which has been raised by the depression of key 46, thereby holding arm 60, arm 63, pawl 64 and bell crank 43 in their actuated positions as shown in Figure 4. At approximately 90° of rotation of pawl 38 and disc 36, pin 77 on the disc 36 engages the upwardly extending arm 69 of pawl 64 and, as shown in Figure 5, rocks the pawl 64 clockwise about its pivot 65 to move square stud 70 from under bell crank 43. Spring 75 then restores crank 43 to its intercepting position, the return of pawl 64 being blocked by the rear arm of bell crank 43 so long as pawl 64 is elevated.

Near the end of the revolution of disc 36 and shaft 28, the stud 44 of clutch pawl 38 is intercepted by crank 43 and is moved radially of disc 36 to disengage the tooth 40 of clutch pawl 38 from the toothed hub 35. During this radial movement, stud 44 engages ear 74 of lever 71 and moves it toward the front of the machine to release tooth 73 from arm 60 thus allowing restoration of the key-operated parts 60, 63 and 64 to their Figure 1 position, stud 70 of pawl 64 moving under crank 43 when arm 63 moves back to normal position. It will be seen that the arm 60 remains operated from the start to the end of the cyclic turn of the disc 36. This is so whether the key 46 is immediately released or not. As will become evident hereinafter so long as the arm 60 remains operated, there can be no institution of a carriage return.

Platen feed mechanism

Each rotation of shaft 28 is transmitted to a platen 78 fixed to a sleeve 79 rotatable in carriage 15 by a train of gearing carried on the carriage 15, the gearing including a gear 81 which is slideable on but rotatable with shaft 28.

Hub 80 of gear 81, Figure 6, is splined to shaft 28 for sliding movement thereon. Hub 80 of gear 81 is also journalled in bearings 82 in a pair of carriage-carried frame plates 83 and 84. Plates 83 and 84, fixedly spaced apart by screws 85 and spacers 86, by engagement with the faces of gear 81, constrain the gear 81 to move with the carriage 15. A gear 89 is journalled in bearings 82

in the forward ends of plates 83 and 84 in a manner similar to gear 81. Hub 90 of gear 89 is freely rotatable on a platen shaft 87, fixed in sleeve 79, but is constrained against endwise movement thereon by the end of sleeve 79 and a collar 96 secured to shaft 87. This gear 89 is connected to gear 81 by a pair of gears 91, 92 rotatable respectively on studs 93 and 94, the studs being fixed in plate 83 and passing through holes in plate 84. The left-hand end of hub 90 is extended to pass through plate 84 to abut the end of platen sleeve 79. A collar 96, formed with a single tooth 97, is fixed to the extended portion of hub 90 by means of a set screw 95.

15 A ratchet gear 98 is secured to the right end of sleeve 79 and carries a pawl 100, Figures 7 and 8, with a tooth 101. Pawl 100 is pivoted on the right side of ratchet gear 98 and is urged inwardly by a spring 104 into engagement with the collar 96 and tooth 97. Fixed to the left end of platen shaft 87 is a line-space ratchet wheel 102 which is driven step by step in the usual manner to feed the paper past the printing line of the type.

Side plate 84 is held against sidewise movement on hub 90 by collar 96 and the left side of gear 89 and plate 83 is similarly held by its connection to plate 84. Referring to Figure 3, it may be seen that the rear end of the frame is likewise constrained to move with the carriage by a plate 99 secured to a bar 103 on carriage 15 and embracing the frame plates 83 and 84.

In operation, the platen shaft 87 will be rotated one or more line spaces as the typing progresses so that pawl 100 fixed to the shaft will rotate ahead while the tooth 97 remains stationary. Upon depression of sweep-feed key 46, the shaft 28 will, as previously set out, be driven one complete revolution. This rotation will be transmitted from shaft 28 by gear 81 splined thereon, through gears 92, 91, and 89 to hub 90 and to tooth 97 on collar 96. The extent of rotation of sleeve 90 and tooth 97 is constant for every turn given the shaft 28, and in the embodiment of the invention shown, equals one turn plus an equivalent of a specific number of line spaces. Obviously, the sizes of gears 81 and 89 are selected in accord with the length of the particular form to be used, and, unless the length of the form is exactly equivalent to the circumference of the platen, the latter will at the end of each form-feeding operation assume a different rotative position. After an idle period of rotation of sleeve 90, as determined by the rotative movements imparted to the platen shaft 87 through line-spacing action, the tooth 97 will engage and pick up the tooth 101 of pawl 100. Further rotation of the gear 89 and tooth 97 will cause rotation of platen shaft 87 by an amount which in reference to the form length is complementary to the extent of rotation given shaft 87 during the typing operation. The additional rotation so given to platen 78 on each cycle of shaft 28, will be appropriate to advance the strip of forms to the first typing line of the next form irrespective of the extent of previous amount of movement given the platen by line-spacing movements.

The platen and bill chute

The forms used in the disclosed embodiment are, as shown in Figure 10, printed on a long strip of paper 106 which is perforated as at 107 for easy separation of the forms. The strip is usually folded along lines 107 into a manifold

pack for convenient handling. The strip 106 is guided about platen 78 by a chute comprising members 108 and 109, Figure 2, having identical sides including openings through which the platen passes. The right chute guide 108 is formed with a depressed extension 110 which passes to the rear of the left guide 109. The guides 108 and 109 are mounted on brackets 111 secured to bar 103 in carriage 15. A weighted bail 112 is located between guides 108 and 109 on a rod 113 and serves to smooth the strip 106 prior to its engagement with the platen 78. Rod 113 is subjected to considerable wear due to vibration of bail 112 and is therefore made lengthwise adjustable to provide new bearing areas for the bail 112. The rod 113 is adjustably held against endwise movement by upturned ears 114 of a pair of stops 115 secured by screws 116 and 117 to brackets 111. Screws 116 pass through slots 118 in stops 115 and when loosened will free stops 115 for adjustment of ears 114 about screws 117. Chute guides 108 and 109 carry set screw collars 119 by which the guides may be fastened to rod 113 to prevent distortion of the forward end of the guides.

It will be noted that the platen 78 has been reduced in length to less than one-half of the usual size. More length is not needed since the strip 106 is narrow and is advantageous since the elimination of the excess length both reduces the force required to prevent overthrow of the platen feed mechanism and allows room for the feed mechanism inside of the carriage end plates, thereby simplifying the construction and assembly. Knobs 120 are fixed to the outer ends of platen shaft 87 to allow a manual line spacing of the platen 78 in either direction. Due, however, to the pawl 100 on ratchet 98 and tooth 97 on collar 96, the platen may not be reversely rotated past the first typing line of the form being typed on but may be rotated forwardly without interference since pawl 100 will freely ride over tooth 97 in this direction.

Overthrow prevention mechanism

A novel mechanism has been provided to prevent an excess rotation of the platen 78 through momentum at the end of its sweep feed. This structure is normally ineffective and is thrown into its active position only at the end of a form-feeding cycle. Restoration of the overthrow preventing means to idle condition is effected under control of the platen as the latter is arrested and over-rotation of the platen is prevented. The platen in its concluding movement, by power of momentum stored therein, acts on and removes the overthrow-preventing means from interference with further platen rotation. This preventing means as shown in Figures 7 and 8 is mounted on the gear frame plates 83, 84 and operative on ratchet wheel 98. In the normal position, Figure 7, a stop lever 123 mounted on stud 94 is normally held in an ineffective position by a spring 125 so that a tail rests against a stud 124 on plate 84. Said spring 125 is connected between the lever 123 and stud 124. An auxiliary stop slide 126 with slots 128 is slidably mounted on a pair of studs 127 on lever 123 and is urged to a forward position by a spring 129 connected between the two levers 123 and 126. In the forward position of slide 126, Figure 8, its stop nose 130 is slightly ahead of the corresponding nose 131 of lever 123.

Fixed to the left end of gear hub 80 on shaft 28, see also Figure 6, is a collar 132 carrying a

projecting ear 133 adjustably secured thereon. In the normal position of shaft 28, as in Figure 7, ear 133 is positioned in front of a projection 134 on the rear end of slide 126 to retain the slide in its rearward position on the lever 123 and so as to allow the lever 123 to occupy its normal position clear of the ratchet wheel 98. Responsive to the operation of the key 46, the shaft 28 rotates clockwise, and thus the ear 133 moves away from the projection 134 to permit spring 129 to move slide 126 to its forward position on the lever 123. Near the end of the full cycle of rotation of shaft 28, see Figure 8, the ear 133 moves under projection 134 to raise the rear end of slide 126 and lever 123 and thereby to depress the stop noses 130, 131 of the lever and slide into the path of one of the teeth of the ratchet wheel 98. The clutch pawl 40 is forced free of the toothed hub 35 before the full revolution of the shaft 28 is completed, but such shaft completes its revolution by stored momentum. Furthermore, due to the acquired inertia of the platen 78, the ratchet wheel 98, and the platen knobs 120, these parts do not stop their counterclockwise rotation when the drive from the tooth 97 ceases. During the continued rotation of platen 78, a tooth of ratchet wheel 98 advances into engagement with the projected nose 130 of slide 126 and forces the slide rearwardly to a position wherein it may drop and be latched behind ear 133. Meanwhile, however, the advancing tooth of the ratchet wheel 98 engages the nose of the lever 123 to prevent further advance rotation of the platen. Since the pivot of lever 123, namely the stud 94, is slightly outside a line tangent to the wheel 98 at a point of contact with nose 130, the lever 123 will not immediately move free of the ratchet wheel 98 when the camming projection 134 moves rearwardly of the ear 133, but will temporarily cling to the engaged wheel tooth. Upon the clash of the wheel tooth with the stop nose 131, there ensues a slight rebound of the wheel and platen, and the spring 125 is resultingly enabled to swing the lever 123 with the slide 126 so as to position the stop noses 130, 131 clear of the ratchet wheel 98. Thus the stop nose 131, comprising the overthrow-preventing means, has been transitorily active.

Platen detent release

A platen detent 137, Figures 7 and 9, carrying a roller 138 is pivoted on stud 93 and tensioned by a spring 139 connected thereto, to engage roller 138 with the teeth of ratchet 98 and thus hold the platen 78 in its adjusted line space positions. The detent roller 138 is located so that the wheel 98 upon arrest by the nose 131 will come to rest in a slight back-up relation with respect to the stopping nose 131, as is clearly evident from Figure 7. During a sweep feed of the platen 78 to advance strip 106 to the next form, it is desirable to release roller 138 from ratchet 98. Collar 132 is formed with a cam notch 140 so positioned that in the normal position of shaft 28, a roller 141 on a plate 142 may enter into the notch 140. Plate 142 is pivoted on stud 94 and tensioned clockwise by a spring 143 connected to its upper end and a convenient part of frame plate 84. A screw 144 is adjustably fixed in an ear 145 of plate 142 and cooperates with a corresponding bent ear 146 on detent lever 137. Collar 132, during the initial part of the rotation of shaft 28, rocks plate 142 counterclockwise and this movement 75 of plate 142 is transmitted through screw 144 to

detent lever 137 thus moving roller 138 to the dotted line position of Figure 7 where it is out of engagement with ratchet 98. At the end of the revolution of shaft 28, roller 138 again drops into notch 140 and frees detent lever 137 for movement into its effective position.

Disabling of form feed mechanism

To insure that a new form will be properly positioned for immediate typing, the effectiveness of the linkage from key 46, Figure 1, to clutch release pawl 64 is placed under control of carriage 15 so that a form-feed cycle can be initiated only in the fully returned position of the carriage. Referring to Figure 3, it may be seen that the upper end of slide 51 is urged to the right end of the slot in bracket 53 by a spring 150 connected between a stud 151 on bracket 54 and a lever 152 pivoted on a stud 153 of slide 51. Another stud 154 on slide 51 is engaged by the lower end of lever 152 to prevent clockwise rotation of lever 152 from its Figure 3 position. In the right-hand position of slide 51, shoulder 56 is not under stud 57 of arm 60 and vertical reciprocation of the slide 51 by key 46 is thus ineffective to initiate a form-feeding cycle. Slide 51 is moved to its effective left-hand position by a tappet 155 on the carriage 15 which will, in the extreme right-hand position of carriage 15, to the left in Figure 3, engage an ear 156 bent off of lever 152 and move shoulder 56 to the effective position under stud 57. It may, however, happen that the form-feed key 46 will be depressed before the carriage has moved into its extreme right-hand position in which case slide 51 cannot move to the left in Figure 3 since stud 57 will engage the side of slide 51. In such case, contact of tappet 155 with ear 156 will rock lever 152 idly about its pivot stud 153. Upon release of key 46, slide 51 is restored to its lower position by spring 157 whereupon spring 150 will move slide 51 to the effective position under stud 157. The key 46, if then reoperated, will institute a form-feeding operation.

Carriage return-form feed interlock

An interlock is provided between the carriage return controls and the form-feed controls to prevent their concurrent operation and possible interference. It is conventional in power typewriters to automatically line space the platen 78 at the conclusion of a carriage return, see for example Patent No. 2,262,676 to Helmond above referred to, and to use the carriage return key for line spacing alone when the carriage 15 is in its fully returned position. Since form feed of the strip 106 involves rotation of the platen 78 through the splined drive afforded by the shaft 28 and the gear hub 80, a simultaneous operation of these two mechanisms might cause damage through stalling of the machine due to excessive friction at the spline fit between the hub 80 and the shaft 28. To prevent such simultaneous operation, an arm 160, Figure 3, with an ear 161 bent from it is mounted on the carriage return initiating lever 23. A plate 162 is fixed to the form-feed arm 60 and will, in the operated position of arm 60, lie over ear 161 and prevent movement of arm 23 for engagement of the carriage return clutch 20. It will be remembered that the arm 60 is moved to operated position by operation of the key 46, and is held thereat by the latch lever 71 until the end of the cyclic turn of the shaft 28, at which time by the outward displacement of the pin 44 of the clutch

dog 38, the lever 71 is restored to the normal non-latching position seen in Figure 1, the arm 60 being consequently allowed to restore. In the event a carriage return is first instituted, the arm 23 will rock anti-clockwise with reference to Figure 3 and the ear 161 of such arm will then lie in the operating path of the plate 162 and will prevent movement of the arm 60 to a clutch-closing position for form-feed.

10 The embodiment disclosed is not the only form which is within the scope of the present invention as various modifications and changes may be made without departing from the invention as set out in the appended claims.

15 What is claimed is:

1. In a typewriter having a frame, and a carriage slidable thereon, the combination of a platen shaft rotatable in said carriage, a platen on said shaft, a motor, and motor operated means to rotate said platen to a predetermined point, said means comprising a shaft supported on said frame, means rotatable on said platen shaft, a member on said platen shaft engageable by said rotatable means in one direction of rotation thereof, carriage-carried means slidable on and rotatable with said frame-supported shaft, means on said carriage operatively connecting said slidable means and said rotatable means, key controlled means driven by said motor to give said shaft single cycles of rotation, and means operated by said slidable means at the end of a revolution of said frame-supported shaft to stop rotation of said platen shaft.

2. In a typewriting machine, a frame, a carriage movable thereon, a platen rotatable in said carriage, a driving member concentric with said platen, a lost motion, one-way connection between said platen and said member, a shaft on said frame, a carriage-carried gear, slidable on said shaft and splined thereto, gearing connecting said slidable gear and said driving member, key controlled means for rotating said shaft, and means to prevent excess rotation of said platen, said means comprising a ratchet wheel fixed to said platen, a stop lever on said carriage, a stop slide on said lever and a cam on said slidable gear, said cam co-acting with said stop slide to depress said lever and slide into blocking engagement with said ratchet wheel whereupon excess rotation of said platen moves said slide to a position free of said cam.

3. In a typewriter having a frame, a carriage movable thereon, a platen in said carriage and a source of power, means to rotate said platen to an advanced position comprising a shaft, driving means between said shaft and said platen, said driving means having a lost motion one-way drive to said platen, a clutch dog on said shaft, a power driven member freely rotatable on said shaft, members to release said dog to permit it to engage said power driven member and to disengage said dog at the end of one revolution of said shaft, a key-operated slide to operate said release members, means normally holding said slide in an ineffective position and means on said carriage to move said slide to an effective position.

4. In a typewriter having a frame, a carriage movable thereon, a platen in said carriage and a source of power, means to rotate said platen to an advanced position comprising a shaft, driving means between said shaft and said platen, said driving means having a lost motion one-way drive to said platen, a clutch dog on said shaft, a power driven member freely rotatable on said shaft, members to release said dog to permit it

to engage said power driven member and to disengage said dog at the end of one revolution of said shaft, a key-operated slide to operate said release members, means normally holding said slide in an ineffective position, means on said carriage to move said slide to an effective position, a cam operated by said shaft, means set by said cam at the end of a revolution thereof to stop rotation of said platen, and means responsive to the arrest of the platen by said cam-set means for resetting said cam-set means to an ineffective position.

5. In a machine of the class described, having a paper-supporting carriage movable on a frame; a paper-feeding roll supported on said carriage to turn on an axis extending parallel to the direction of carriage movement, means movable along with the carriage and operable to impart rotative movements to said roll which place the latter in different rotative positions, said rotation imparting means including a rotatable element having an axis extending parallel to the carriage, power-means to impart a single rotation to said element, comprising, a one-revolution clutch on the frame axially in alignment with said element, and means including shaft means extending parallel to the direction of carriage movement, connecting said clutch operatively with said element in any position of the carriage, a circular array of teeth associated for rotation in step with said roll, and means on the carriage, responsive to said element at the end of each revolution imparted thereto, to move into rotation limiting relation with said teeth, thereby to stop rotation of said roll.

6. In a machine of the class described, having a paper-supporting carriage movable on a frame; a paper-feeding roll supported to turn on said carriage, means movable along with the carriage and operable to impart rotative movements to said roll which place the latter in different rotative positions, said rotation imparting means including an element having an axis extending parallel to the carriage, power-means to impart a single revolution to said element, comprising, a one-revolution clutch on the frame axially in alignment with said element, and means including splined shaft means extending parallel to the direction of carriage movement, connecting said clutch operatively with said element in any position of the carriage, means on the carriage, responsive to said element at the end of each revolution imparted thereto, to stop rotation of said roll, a key-control on the frame operable to close said clutch for one revolution of said shaft means, and means including a control element on the carriage to incapacitate said key-control in all but a returned position of the carriage.

7. In a machine of the class described, having a paper-feeding roll, a wheel associated with said roll and having teeth forming notches defining line-space positions, a line-space detent normally in engagement with any wheel notch, means operable to impart extensive rotative movements to said roll which place said roll in different line-space positions, an element which is given a single revolution each time said operable means is to impart a rotative movement to said roll, means normally clear of said detent wheel and transitorily responsive to said element at the end of each revolution to move into rotation limiting engagement with the teeth of said wheel, and means including control means on said element, to release said detent at the outset of each revolution

of said element and to apply it again when the revolution nears conclusion.

8. In a machine of the class described having a paper-feeding roll and a turning member for said roll, means always rotarily connected with said roll and comprising teeth arranged in a circular array and defining a series of different rotative positions for said roll, a single revolution element, power means to impart single revolutions to said element, motion transmitting means always ready to transmit motion from said element to said member and at a ratio for said element at each revolution thereof to drive the roll to one of the said rotative positions defined by said teeth, a device conditionable for roll-stopping coaction with any one of said teeth arriving at a certain position at the end of each revolution of said element, means on said element and in control over said device to condition the latter at the conclusion of each revolution of said element, and means responsive to the ensuing roll-stopping coaction of said device with one of said teeth to place said device automatically in ineffective condition permitting impartation of a new revolution to said element.

9. In a machine of the class described having a paper-feeding roll and a turning member for said roll, means constantly connected to said member and operable to impart rotative movements thereto which will place such roll in any one of a number of evenly spaced rotative positions, said operable means including an element which is given a single revolution for imparting each of said rotative movements to said roll, a circular array of teeth associated with said roll for rotation concentrically therewith, said teeth circularly spaced in conformance with the rotative positions of the roll, and means responsive to said element near the conclusion of each revolution thereof to move into the path of said teeth for roll-stopping coaction with one of said teeth, and responsive to said roll-stopping coaction with any of said teeth to move automatically clear of the path of said teeth and permit impartation of a new rotation to said element.

10. In a machine of the class described, having a carriage movable on a frame and having a paper-feeding roll mounted on the carriage to turn on a certain axis, means to power-rotate said roll, comprising, a shaft rotatably mounted on the frame and extending parallel to the carriage, on an axis different from that of said roll, an element turnable by said shaft and having a splined connection therewith for movement along said shaft, means on the carriage to cause said element to move along with the carriage, means to transmit rotary motion from said element to said roll, and power means to impart single rotations to said shaft, means always rotarily connected with said roll and comprising a tooth moved toward a certain location each time said element approaches the end of a rotation, a device conditionable for roll-stopping coaction with said tooth, means on said element in control over said device to condition it at the conclusion of each rotation of said element for roll-stopping coaction with said tooth, and means responsive to the ensuing roll-stopping coaction of said device with said tooth to place said device automatically in ineffective condition to permit impartation of a new rotation to said element.

11. In a machine of the class described having a paper-feeding roll, a rotary element, power means to impart single rotations to said element,

gear means to transmit rotary movement from said element to said roll, a line space detent wheel associated with said roll and provided with detent notches, a detent normally engaged with said wheel in one of its notches, and means to release said detent during each rotation of said element, comprising, a cam unitary with said element, and means including a follower controlled by said cam and operatively connected with said detent to release the latter at the beginning of each single rotation of said element and to apply it again automatically at the end of the same rotation.

ARTHUR H. SHARPE.
